Des. 192,553
Patented Apr. 10, 1962

192,553

SOLE FOR A BOOT OR SIMILAR ARTICLE OF FOOTWEAR

Abraham Messinger, Larchmont, N.Y., assignor to Vlyt Corporation, New York, N.Y.

Filed Oct. 26, 1961, Ser. No. 67,270

Term of patent 14 years

(Cl. D7—5)

FIGURE 1 is a bottom plan view of a sole for a boot or similar article of footwear embodying my new design, and,

I claim:

The ornamental design for a sole for a boot or similar article of footwear, as shown.
